Primary Examiner — Catherine Tuttle**CLAIM**

(57) The ornamental design for a combined sprayer and refill bottles, as shown and described.

DESCRIPTION

FIG. 1 is a top, right, front perspective view of a combined sprayer and refill bottles embodying our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear view thereof; and,

FIG. 7 is a bottom plan view thereof.

The broken lines are included for the purpose of illustrating portions of the combined sprayer and refill bottles that form no part of the claimed design.
